UNITED STATES PATENT OFFICE

154,070

DESIGN FOR A SCOOTER

David M. Simpson, Hawthorne, Calif.

Application February 9, 1948, Serial No. 144,367

Term of patent 3½ years

(Cl. D34—15)

To all whom it may concern:

Be it known that I, David M. Simpson, a citizen of the United States of America, residing in Hawthorne, in the county of Los Angeles and State of California, have invented a new, original, and ornamental Design for a Scooter, of which the following is a specification, reference being had to the accompanying drawing, forming part thereof.

Fig. 1 is a top plan view of a scooter, showing my new design.

Fig. 2 is a side elevational view thereof.

Fig. 3 is a front elevational view.

The dominant features of the design are shown in full lines.

I claim:

The ornamental design for a scooter, substantially as shown and described.

DAVID M. SIMPSON.
